HYDRAULIC HOIST

Charles G. Eisenberg, Jr., Wauwatosa, Wis., assignor to The Heil Co., Milwaukee, Wis., a corporation of Wisconsin

Application March 15, 1937, Serial No. 130,958

8 Claims. (Cl. 60—52)

My present invention relates in general to improvements in systems for actuating mechanisms by fluid pressure, and relates more specifically to improvements in the construction and operation of hydraulic hoists and similar or allied hydraulically operated devices.

Generally defined, an object of my present invention is to provide an improved hydraulic hoist system which is simple and compact, yet highly flexible and efficient in use.

When utilizing hydraulic hoists for the operation of dump bodies and other accessories mounted upon vehicles, it frequently becomes desirable in order to conserve power and space, and to simplify the system, to employ the same pressure producing unit or pump for the purpose of actuating all of the fluid operated mechanisms. Since the body actuating hoists of such systems are usually most important of the fluid operated mechanisms, the pressure producing pump is preferably more closely associated with these hoists than with the other accessories; and because of the fact that the body actuating hoist cylinders ordinarily are swingable relative to the vehicle chassis about pivot trunnions, and that the pump is preferably mounted directly upon and is swingable with these cylinders, it becomes quite a problem to utilize this pump for actuating other hydraulic hoists or jacks mounted upon the same vehicle but which are not suspended from the body actuating hoists. In cases where these hydraulically actuated mechanisms are rather numerous, or require relatively large volumes of liquid, a rather large liquid supply reservoir is required; and this reservoir is then preferably mounted directly upon the vehicle chassis independently of the hoists, but because the common pump for all hydraulic devices is preferably suspended from the movable body hoists, the supply of liquid for operating all of the accessories must naturally pass through the movable hoist and pump assemblage. The system must also be relatively leakproof in order to eliminate loss of actuating fluid which usually is oil, and all of these desirable conditions and requirements introduce many difficult problems.

It is therefore a more specific object of the present invention to provide an improved hydraulic system for actuating various accessories mounted upon a common vehicle, wherein the pressure producing pump is carried directly by the movable main hoist cylinders and is effectively utilized to actuate other accessories.

Another specific object of my invention is the provision of a vehicular hoist system wherein a

twin cylinder hydraulic hoist having a liquid circulating pump mounted directly upon the cylinders thereof is utilized to actuate one movable part such as the dump body, and in which the same pump is also employed to circulate liquid under pressure through other accessories such as the hydraulic jacks for operating a snow plow, a dump-body tail gate, and the like.

A further specific object of the present invention is to provide an improved twin hydraulic hoist assemblage wherein the hoist cylinders are swingably supported, and in which the actuating liquid is effectively conducted to the cylinders from an extraneous source and is returned from the cylinders to the source, without leakage.

Still another specific object of my invention is the provision of a new and useful trunnion supported double cylinder hoist having the circulating pump supported by and swingable with the cylinders and supplied with actuating fluid from a fixed storage reservoir, the same pump also being adapted to furnish liquid under pressure for the actuation of other mechanisms.

These and other objects and advantages of my present invention will be apparent from the following detailed description.

A clear conception of an embodiment of the several features constituting my improvement, and of the mode of constructing and of utilizing hydraulic hoist systems built in accordance with the invention, may be had by referring to the drawings accompanying and forming a part of this specification wherein like reference characters designate the same or similar parts in the various views.

Fig. 1 is a part sectional fragmentary front view of a twin cylinder, telescopic, trunnion supported hydraulic hoist and circulating pump assemblage, looking toward the pump;

Fig. 2 is a part sectional fragmentary side view of the assemblage of Fig. 1, the section being taken along the line 2—2;

Fig. 3 is a transverse horizontal section through the hoist and pump assemblage of Fig. 2, taken along the line 3—3;

Fig. 4 is a transverse section through the liquid conducting joint which is disposed between the twin cylinder of the main hoist; and

Fig. 5 is a diagram showing a system wherein the improved hoist may be used advantageously.

While my invention has been shown and described herein as being specifically applied to a telescopic twin hydraulic hoist cooperating with hydraulic jacks for actuating a dump-body tail gate and a snow plow, it is not my intent to

thereby unnecessarily restrict the scope, since some of the improved features may obviously be advantageously applied in other types of systems.

Referring to the drawings, and especially to the diagram of Fig. 5, the improved hydraulic system shown therein comprises in general a main hydraulic hoist having twin cylinders 8 pivotally suspended at their upper ends from a vehicle chassis 9, and having therein telescopic pistons 10; a dump body 11 swingably attached at its rear portion to the chassis 9 and pivotally connected at its forward portion to the upper ends of the inner pistons 10 by means of pivot pins 12; a tail gate 13 associated with the rear end of the body 11 and being operable by an auxiliary hydraulic hoist or jack 14 also mounted upon the chassis 9; another auxiliary hydraulic hoist or jack 15 mounted upon the chassis 9 and cooperable through linkage 16 with a snow plow or the like; a liquid supply reservoir 17 supported directly upon the chassis 9 independently of the hydraulic hoists; and a single liquid circulating pump 18 carried by and movable with the main hoist cylinders 8, for delivering liquid from the reservoir 17 to the cylinders 8 and to the hydraulic jacks 14, 15. It is to be understood that Fig. 5 is merely a diagram and does not show the parts in their actual shapes, sizes or locations; and the auxiliary jacks 14, 15 are alternately but not simultaneously operable, being controlled by means of a three-way valve 19.

The twin hydraulic cylinders 8 are spaced apart as shown in Figs. 1, 2 and 3, and are pivotally suspended from the chassis 9 by means of aligned trunnions 20 coacting with the outer sides thereof. Each of the cylinders 8 is provided with a similar liquid conducting port 21, 22 at its upper end, and the ports 21, 22 of the two cylinders 8 communicate with the opposite ends of a conduit forming joint interposed between the cylinders 8 in line with the supporting trunnions 20. This joint is shown in detail in Figs. 2, 3 and 4, and comprises a stationary part or element 23 having a duct 24 which constantly connects the cylinder port 21 with a stationary pipe 25 leading to the supply reservoir 17, and having another duct 26 segregated from the duct 24 and constantly connecting the cylinder port 22 with another stationary pipe 27 leading to the control valve 19 of the jacks 14, 15. The ends of the element 23 abut against the inner sides of the cylinders 8 and are circular in cross-section, being snugly embraced by packings 28 confined in adjustable glands 29 carried by and oscillatable with the hoist cylinders 8, as clearly shown in Figs. 3 and 4. The liquid conducting joint assemblage is obviously so constructed that it will permit liquid to flow from the stationary supply reservoir 17 to the cylinder port 21 through the pipe 25 and duct 24, and from the port 22 to the jacks 14, 15 through the duct 26 and pipe 27, while also permitting free oscillation of the main hoist cylinders 8 about the trunnions 20, but without permitting the liquid to escape at the joints.

The single liquid circulating pump 18 is of the well known gear type, and is adapted to be driven from the propelling motor of the vehicle, through a driving connection 30. This pump 18 is mounted directly upon the front of a manifold 31 rigidly attached to the forward upper portions of the cylinders 8; and a control valve 32 which is operable by a lever 33, is mounted upon the rear medial face of the manifold 31. The manifold 31 and the control valve casing are provided with

communicating suction ports 34 which communicate directly with the pump 18 and are in constant communication with the reservoir 17 through the cylinder port 21, duct 24 and pipe 25, and these elements are also provided with communicating pressure ports 35 which communicate with the pipe 27 and control valve 19 for the auxiliary jacks 14, 15 through the port 22 and duct 26 past a pump discharge valve 36, see Fig. 2. The control valve casing and manifold 31 are moreover provided with communicating ports 37 which communicate with the upper ends of ducts 38 leading into the lower ends of the cylinders 8, as shown in Figs. 1 and 2, and the pump suction and discharge ports 34, 35 are adapted to be alternately connected with both of the ports 37 by a peripheral recess 39 in the valve 32. The valve 32 is also provided with an opposite peripheral recess 40 which is connected with the recess 39 by a port 41, and the valve 32 is also pierced longitudinally by a port 42 so as to balance the pressures acting upon opposite faces of the valve body. It is to be noted that when the pump 18 is operating, the suction opening thereof is in constant open communication with the liquid supply reservoir 17 through the suction port 34, cylinder port 21, duct 24 and pipe 25, and the pump will then deliver liquid under pressure past the discharge valve 36 into the ports 35 which communicate through the ports 22, duct 26 and pipe 27 with the jack control valve 19.

Besides the manifold 31, the main hoist cylinders 8 may be interconnected by means of a cross-beam 43 which is recessed as shown in Fig. 1, to clear the pipes 25, 27 during oscillation of the cylinders 8. A screw jack 44 may also be provided between the cylinders 8 near the joint element 23, in order to adjust the clearance between the ends of this element and the adjacent faces of the cylinders at the glands 29. The main hoists are of the single acting telescopic type, and the liquid ordinarily utilized in the system, is oil of which there should be an abundant supply in the reservoir 17.

During normal operation of the improved hydraulic system and assuming the pump 18 to be operating, the three-way control valve 19 for the auxiliary jacks 14, 15 would normally be set to cut off communication between these jacks and the pressure supply pipe 27. The main hoist is then operable independently of the jacks 14, 15 to control the raising or lowering of the pistons 10, by manipulation of the control valve 32 alone. When the valve 32 is set in the position shown in Fig. 2, with the recess 39 connecting all of the ports 34, 35, 37, the pump 18 will merely be circulating oil from the suction ports 34 past the discharge valve 36, through the ports 35 and valve recess 39 back into the suction ports 34. Since this freely circulating oil is not under pressure, and in view of the fact that the ducts 38 are in open communication through the ports 37 with the recess 39 and suction ports 34, the pistons 10 and the body 11 will be free to descend by gravity and will force oil from within the cylinders 8 through the ports 34, 21, duct 24 and pipe 25 into the supply reservoir 17 until the pistons 10 are completely lowered. In order to subsequently elevate or raise the pistons 10 and body 11, it is only necessary to swing the lever 33 so as to move the valve 32 in a counter-clockwise direction from the position shown in Fig. 2, sufficiently to cut off communication between the suction ports 34 and the valve recess 39 while maintaining the communication be-

tween the ports 35, 37 through this recess. The pump 18 will then suck oil from the supply reservoir 17 through the pipe 25, duct 24, and ports 21, 34; and will deliver this oil under pressure past the valve 36 and through the ports 35, recess 39, ports 37 and ducts 38 into the cylinders 8, whereupon the pistons 10 will be elevated to tilt the dump body 11. Lowering or raising of the dump body 11 may thus be quickly effected by merely manipulating the valve 32 with the aid of the lever 33.

If the valve 32 is set for raising of the pistons 10, the pump discharge ports 35 and the passages communicating therewith, will be filled with oil under pressure; and in order to then elevate either of the jacks 14, 15, it is only necessary to adjust the control valve 19 so as to permit oil to escape to the jack which it is desired to operate through the port 22, duct 26 and stationary pipe 27. The elevated jack 14, 15 may thereafter be lowered or reversely operated simultaneously with the lowering of the main pistons 10, by merely setting the main control valve 32 into the position shown in Fig. 2, whereupon the pressure in the ports 35 will be released as previously described. If such simultaneous lowering of the auxiliary jack is not desired, the valve 19 may be adjusted to retain oil under pressure within the elevated jack while the main hoist pistons 10 are being lowered. In case the main pistons 10 have been previously lowered, and it becomes desirable to lower the elevated jack 14, 15, it is only necessary to position the valve 32 as in Fig. 2 and to thereafter set the valve 19 so as to permit escape of the liquid under pressure from within the elevated jack through the pipe 27, duct 26 and ports 22, 35 to the suction port 34 through the valve recess 39. This reverse operation of the jacks 14, 15 may be effected even if the pump 18 is at rest, and the excess oil from the jacks will be returned to the supply reservoir 17 through the ports 34, 21, duct 24 and pipe 25. In case it is desired to actuate or elevate either of the jacks 14, 15 without elevating the main hoist pistons 10, the pump 18 should be placed in operation, the main valve 32 should be swung in a clockwise direction from the position shown in Fig. 2 sufficiently to close off communication between the ports 35, 37, and the control valve 19 should be set to connect the desired jack with the pressure supply pipe 27, whereupon oil under pressure will be delivered to the selected jack 14, 15 only. It will thus be apparent that the main hoist may be raised or lowered alone, and that either of the jacks 14, 15 may also be raised or lowered alone, or either jack may be raised or lowered simultaneously with the main hoist. From the foregoing detailed description it will be apparent that the several hydraulic devices may be independently operated without in any manner interfering with the operation of the others, and the single supply reservoir 17 furnishes actuating fluid for all of the hydraulic devices. It will also be apparent that the single pump 18 supplies liquid under pressure to all of the hydraulic devices, and because of the fact that this pump 18 is supported by and oscillates with the main hoist, the joint which is interposed between the cylinders 8 makes it possible to utilize this common pump to so supply the fluid under pressure. All of the oil which passes to the several hydraulically operated devices, must pass through the joint elements 23 whether this oil flows from the reservoir 17 into

these devices, or when returning to the reservoir 17. Because of the fact that the joint element 23 is mounted between the cylinders 8 in alignment with the trunnions 20, this joint element may be maintained stationary with respect to the chassis 9, and the glands 29 cooperating with the packing 28 effectively prevent escape of oil past the joints. The improved twin hoist assemblage is relatively simple and compact in construction and has proven highly efficient in commercial operation, and while the specific hoist shown is of the telescopic twin cylinder type, it should be obvious that the invention is also applicable to other types of hydraulic hoists. By mounting the liquid supply reservoir 17 independently of the main hoist, a tank of relatively large capacity may be utilized for supply purposes, and it will be apparent that a relatively large tank is necessary where telescopic hoists are employed. The detailed construction of the valves 19, 32 may obviously be varied to suit specific conditions, but the main valve 32 is preferably balanced in the manner shown in order to permit ready operation thereof. As previously indicated, the pump 18 is of the gear type, although any other suitable type of pump may be employed in the improved system; and this pump may in some cases be mounted independently of the main hoist cylinders and will still permit advantageous use of the improved joint for distributing the liquid through the main cylinder ports and passages to the auxiliary jacks and to the supply reservoir. The formation of the main hoist cylinders with these oil distributing ports and passages in the walls thereof and cooperating with a joint for conducting liquid to and from these passages, is an important feature of the present invention, regardless of the specific disposition or mounting of the pump 18, reservoir 17, or jacks 14, 15.

It should be understood that it is not desired to limit this invention to the exact details of construction or to the precise mode of operation herein shown and described, for various modifications within the scope of the claims may occur to persons skilled in the art.

I claim:-

1. In combination, a hydraulic hoist having a pivotally suspended cylinder and a piston movable therein, a pump mounted upon and swingable with said cylinder, said pump being operable to deliver liquid into said cylinder to move said piston, a liquid supply reservoir supported independently of said cylinder, means including a joint having parts relatively movable about the axis of suspension of said cylinder and forming a conduit for conducting liquid from said reservoir to said pump, and means forming a conduit for conducting liquid under pressure from said pump through said joint to other hydraulic devices supported independently of said cylinder.

2. In combination, a hydraulic hoist having a pair of laterally spaced cylinders each having a piston movable therein and being swingable about a common axis, a pump mounted upon and swingable with said cylinders, said pump being operable to deliver liquid into said cylinders to move said pistons, a liquid supply reservoir supported independently of said cylinders, conduit means including a joint disposed between said cylinders and having parts relatively movable about said axis for conducting liquid from said reservoir to said pump, and means forming a conduit for conducting liquid under pressure from said pump through said joint to

other hydraulic devices supported independently of said cylinders.

3. In combination, a twin hoist having a pair of laterally spaced parallel hydraulic cylinders each having a piston movable therein and both being swingable about a common axis at the upper ends thereof, a pump mounted directly upon said cylinders near said axis, said pump being operable to deliver liquid into both of said cylinders to simultaneously move said pistons, a liquid supply reservoir supported independently of said cylinders, conduit means including a joint disposed between said cylinders and having fixed and movable parts relatively swingable about said axis for conducting liquid from said reservoir to said pump and from said cylinders to said reservoir, and means forming a conduit for conducting liquid under pressure from said pump through said joint to other hydraulic devices supported independently of said cylinders.

4. In combination, a hoist having a hydraulic cylinder having a movable piston therein and being swingable about an axis at the upper end thereof, a trunnion coacting with one side of said cylinder at said axis, a liquid conducting joint having a stationary part coacting with the opposite side of said cylinder at said axis, a liquid circulating pump carried by said cylinder and communicating with the latter to deliver actuating liquid to said piston and also communicating with said joint, a liquid supply reservoir communicating with said stationary part of said joint, and other hydraulic devices communicating with said pump and with said reservoir through said joint.

5. In combination, a twin hoist having laterally spaced hydraulic cylinders each having a piston movable therein and both being swingable about a common axis, trunnions coacting with the outer sides of said cylinders at said axis, a liquid conducting joint having a stationary part disposed between and coacting with the inner adjacent sides of said cylinders at said axis, a liquid circulating pump carried by said cylinders and communicating with said joint and with said cylinders to deliver actuating liquid to said pistons, a liquid supply reservoir communicating with said stationary part of said joint, and other hydraulically operated appa-

ratus communicating with said reservoir and with said pump through said joint.

6. In combination, a twin telescopic hoist having laterally spaced hydraulic cylinders each having a movable piston therein and being swingable about a common horizontal axis, trunnions coacting with the outer sides of the upper portions of said cylinders in alignment with said axis, a liquid conducting joint having a stationary part disposed between and coacting with the inner adjacent sides of said cylinders concentrically of said axis, packings interposed between the ends of said stationary joint part and each of said cylinders, a liquid circulating pump carried by said cylinders and communicating with said joint and with said cylinders to deliver liquid to said pistons, a stationary liquid supply reservoir communicating with said stationary joint part, and a hydraulic device mounted independently of said cylinders and receiving fluid under pressure from said pump and from said reservoir through said joint.

7. In combination, a hydraulic hoist having a pivotally suspended cylinder and a movable piston therein, a pump for delivering liquid into said cylinder to move said piston, a liquid supply reservoir supported independently of said cylinder, means including a joint having parts relatively movable about the axis of suspension of said cylinder and forming a conduit for conducting liquid from said reservoir to said pump, and means forming a conduit for conducting liquid under pressure from said pump through said joint to other hydraulic devices supported independently of said cylinder.

8. In combination, a hydraulic hoist having a pivotally suspended cylinder with a movable piston therein and being provided with a liquid distributing port leading to the cylinder in line with the supporting pivot thereof, a pump for delivering liquid into said cylinder to move said piston, a liquid supply reservoir, means including a joint having a stationary part communicating with said cylinder port for conducting liquid from said reservoir to said pump, and means forming a conduit for conducting liquid from said pump through said joint and away from said cylinder.

CHARLES G. EISENBERG, JR.
